ATTORNEY.

UNITED STATES PATENT OFFICE.

JOHN FRANCIS BURDETT, OF LOWELL, MASSACHUSETTS.

CASH-CARRIER APPARATUS.

SPECIFICATION forming part of Letters Patent No. 381,052, dated April 10, 1888.

Application filed July 11, 1887. Serial No. 243,980. (No model.)

To all whom it may concern:

Be it known that I, JOHN FRANCIS BURDETT, a citizen of the United States, residing at Lowell, in the county of Middlesex and State of Massachusetts, have invented certain new and useful Improvements in Cash-Carrier Apparatus, of which the following is a specification, reference being had therein to the accompanying drawings, in which—

10 Figure 1 is a side elevation of my improvement in position; Fig. 2, a vertical longitudinal section of the same detached; Fig. 3, a similar section in another position; Fig. 4, a plan; and Figs. 5 and 6 are perspective details.
15 This improvement relates to that class of cash-carriers in which a car runs on a wire track; and the invention consists in the peculiar combinations, construction, and arrangement of parts, hereinafter more particularly 20 described, and then definitely pointed out in the claims.

Referring now to the details of construction, A represents a hanger or standard, in which is screwed the tube B, which receives 25 the spiral spring C. This tube is slotted at b and is provided with the wire guides D and spring-latches E which project over the inclined slots b'. In the slot b travels the upper catch, F, (see Fig. 4,) which has projecting 30 pins f, that slide under the edges of the slotted part of the tube. Attached to the catch in any convenient manner is the cord G, which passes over the grooved pulley H, as shown. In front of the spring is a head, I, (see Fig. 35 6,) provided with an opening, i, to receive a buffer, J. Pivoted to a lug, K, projecting from the head I, is second or lower catch, L, which is held in an operative position by the spring l. At M is shown a cord, which is connected to the catch F in any convenient manner and passes through an eye, N, (attached 40 to the tube,) and downward below the same to a weight, O. Preferably, two cords are employed, as shown in Fig. 4, both of which are united to the weight. At P is shown the wire track on which the carrier or carriage Q runs, which carrier is provided with the projection R and notch S at both ends, as shown.

Instead of the spiral spring an elliptical

spring may be used, as shown in dotted lines, 50 or I may use both.

I may sometimes use both catches together, as shown, or I may dispense with one of them, according to circumstances.

The operation is as follows: When the carrier is run up against the buffer, it slightly pushes back the head I and runs between the upper and lower catches (or under the upper one, if the lower one be removed) and is there caught. If, now, the catch F be pulled back 60 by the cord G, it will draw the carrier back with it until the pins f rise up through the slots b' and pass under the spring-latches E, which raises the catch and thus liberates the head, which is now driven out by the pressure 65 of the spring at a great speed and impels the car at a corresponding speed. As the lower catch is inclined and the notch S has also an inclined side, said catch will not hold the car when it is driven out by the springs, as the 70 impetus derived from the spring will cause it to slip out of the notch, in the lower catch. When the cord G is released, the weight O, drawing on the cords M, draws the catch forward again to its original position, the pins 75 in the catch sliding under the spring-latches.

Having thus described what I consider the preferable mode of carrying out my invention, but without limiting myself to the exact construction shown, I claim as new—

80

1. The combination, in a cash-carrier apparatus, of a carrier, a track for the same, a spring for impelling the carrier, a stationary tube inclosing said spring, and a catch adapted to move on said tube for holding the carrier 85 and constructed to move in one direction independent of the spring, substantially as described.

2. The combination, in a cash-carrier apparatus, of a carrier, a track for the same, a spiral spring for impelling the carrier, a catch to hold said carrier, and a stationary tube forming a guide for spring and catch, and a supplemental catch carried by said spring, substantially as described.

95

3. The combination, in a cash-carrier apparatus, of a carrier, a track for the same, a spring for impelling the carrier, a catch to

hold said carrier, and a tube forming a guide for the spring and carrier, having the inclined slots *b* and latches *E*, substantially as described.

5 4. The combination, in a cash-carrier apparatus, of a carrier, a track therefor, a spring for impelling the carrier, a catch for holding said carrier, a cord for compressing the spring, and another cord and weight independent of the propelling spring for drawing forward the

catch passed through the eyes *N* on the forward end of the tube, substantially as described.

In testimony whereof I affix my signature in presence of two witnesses this 28th day of June, 1887.

JOHN FRANCIS BURDETT.
